UNITED STATES PATENT OFFICE

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT

LOCK

Application filed April 13, 1929. Serial No. 354,723.

This invention comprehends certain new and useful improvements in locks and is of particular value in connection with locks for hotel sleeping rooms.

The general object of this invention is to provide certain improved features of construction which lend themselves to simplicity, economy of construction, durability and safety. Specifically these various objects will appear clearly to one skilled in the art from a reading of the following description and an examination of the accompanying drawings, in which—

Fig. 1 is a side elevation of my new lock with the cap removed to show the internal construction and arrangement of parts;

Fig. 2 is a similar view with part of the cap in place showing certain internal parts in a different position from that indicated in Fig. 1;

Fig. 3 is a perspective view showing the parts somewhat separated or offset;

Fig. 4 is a horizontal cross-section of the lock case on the plane of the dead-bolt showing in plan certain of the internal parts;

Figs. 5 and 6 are respectively views of two different keys adapted to the lock;

Fig. 7 is a plan view of a detail.

1 is the lock case. 2 is the cap. 3 is the face-plate. 4 is the spring latch-bolt. 5 is a dead-bolt. 6 is a cylinder lock mounted on the outside of the case 1. 7 is a roll-back mounted in the case 1 and designed to be operated by the usual knob (not shown) at the inside of the door so that by turning such a knob the latch-bolt 4 will be retracted through the medium of a lever 8 and the latch-bolt tail 9. 10 is another lever for retracting the latch-bolt 4. This lever is pivoted at 11 in the lock case, and is itself operated by still another lever 12 pivoted at 13 in the lock case. When the parts stand as shown in Fig. 1 this lever 13 may be swung to retract the latch-bolt 4, by the turning of the cylinder lock roll-back 14 in a clockwise direction. The normal position of this cylinder lock roll-back 14 is shown in Fig. 3, and when a proper key is introduced to release the cylinder lock plug, this roll-back may be turned in either direction. With the parts as

shown in Fig. 1, the latch-bolt 4 may be retracted by the use of either of the keys P or E (Figs. 5 and 6), the former being the regular key such as would be furnished the user of the room and a floor attendant, the latter being a special key ordinarily kept in the possession of the proprietor and used for certain emergencies. In the particular cylinder lock shown, the roll-back 14 is provided with an auxiliary slidable head 15 which is normally retracted so as to stand in the position shown in Fig. 3. When the key P is inserted in the cylinder lock, it, being short, will have no effect on the position of the head 15. When, however, the special key E is inserted, it, being longer, will cause the head 15 to project outwardly to the position shown in Figs. 1 and 2, in which position it serves to perform a certain function designed only to be performed by the use of the emergency key E.

The dead-bolt 5 is provided with a tail portion of unique design and construction certain parts of which may best be seen in Fig. 3, in which it will be noted that the upper rear end of the tail is recessed at 16. 17 is a stop shoulder at the rear of this recess 16. This dead-bolt tail is also provided with a passage 19 to provide clearance for a roll-back hub 20 which is mounted to rotate in the lock case. 21 is a horizontal slot in the tail of the dead-bolt into which projects a fixed post or stump 22 to guide the rear end of the dead-bolt tail as it is reciprocated. On the lower part of the latch-bolt tail are two more stop shoulders 23—24 on opposite sides of a lower passage. These are best seen in Figs. 1 and 2. 25 is a lever pivoted at 26 on the side of the dead-bolt 5. The rear end of this lever extends up into the recess 16 so as to be engageable by the head 15 of the cylinder lock-roll-back when the emergency key E is used and by which head only can it be depressed sufficiently far to accomplish the releasing of the dead-bolt so that the latter may be projected from the position shown in Fig. 1 to that shown in Fig. 2. Before describing this operation, it is desirable to describe the construction of the roll-back 20. This roll-back is provided with two diametrically opposed wings or arms 27—28

and at right angles to said wings 27-28 is another arm or wing 29. 30 is a rounded nose portion on the end of the wing 29. 31 is a lever pivoted at 32 on the lock case. 33 is a spring for impelling said lever toward the nose 30 of the roll-back 20. The free end of the lever 31 is provided with inclines 34-35. The hub of the roll-back 20 is provided with the usual spindle passage for receiving the ordinary thumb turn 18 such as located on the inside of the door to which the lock is applied so that any one in the room may, by rotating said thumb turn only a quarter of a turn project or retract the dead-bolt. The occupant of the room may thus be afforded the double security of a dead-bolt and a latch-bolt, neither of which can be operated from the outside of the door except by the use of a suitable key.

20. If the parts stand as shown in Fig. 1 with the dead-bolt retracted, the holder of either one of the keys P or E may retract the latch-bolt by inserting the key in the cylinder lock and turning the roll-back in a direction to engage the lever 12, which when tilted will retract the latch 4 through the medium of the lever 10. When, however, the dead-bolt 5 is projected as shown in Fig. 2, the lever 12 will be tilted from the position shown in Fig. 1 to that shown in Fig. 2, so that its end will stand out of range of the roll-back 14 and its head 15. This tilting of the lever 12 is effected by the shoulder 36 which simply rides under an incline 37 on the lever 12 when the dead-bolt 5 is projected, thus lifting the latter. It follows that when the occupant of a room has closed his door and has projected the dead-bolt 5 by the use of a thumb turn associated with the roll-back 20, the room cannot be entered by the floor attendant or chambermaid who is provided only with a regular key P. If, however, access is necessary, the proprietor may use his special emergency key E which is so designed as to cause the head 15 on the cylinder lock roll-back to be projected so that by turning said cylinder lock roll-back in a clockwise direction, the head 15 will be brought into contact with the lever 25 (Fig. 2) depressing the same. The rear end of the lever will be seen to rest on the wing 28 of the roll-back 20. Hence, as the lever 25 is depressed this roll-back 20 will be rotated in a clockwise direction, the effect of which is to move the ends of the arms 27-28-29 to a position where they are free of the stop shoulders on the dead-bolt tail thus leaving the dead-bolt free to be reciprocated by the end of the cylinder lock roll-back. When the cylinder lock roll-back has been rotated from the position shown in Fig. 2 to that shown in Fig. 1, the dead-bolt 5 will be fully retracted at which time the roll-back 20 will also be shifted, by the action of the dead-bolt tail on arm 29, from the position shown in Fig. 2 to

that shown in Fig. 1, wherein the arms 27-29 will stand in front of the shoulders 17-23 to positively hold the dead-bolt retracted. The owner of the emergency key E may advance the dead-bolt by simply reversing the direction of rotation of the key until the dead-bolt 5 is fully projected whereupon the roll-back 20 will resume the reversed position shown in Fig. 2, and the wing 29 will stand at the rear of the stop shoulder 24 of the dead-bolt 5 to positively hold the latter projected. It will be understood that the function of the lever 25 is partly to frictionally hold the roll-back 20 in its two operative positions indicated respectively in Figs. 1 and 2, and partly to throw the roll-back to its extreme dead-bolt blocking positions when the dead-bolt is fully advanced or fully retracted, the roll-back being displaced from said positions when operated by the key. By the first depressing movement of the lever 25, after which as the cylinder lock roll-back is turned to reciprocate the dead-bolt, the movement of said dead-bolt will rotate the roll-back 20 through the medium of the arm 29 which is then positioned in the notch or opening between the shoulders 23-24.

Inasmuch as the operation of the various parts has been described as incidental to the description of the construction, it is unnecessary to repeat the same at length further than to say that when the lock is operated by any regular key P such as shown in Fig. 5 and such as provided to the guest and the chambermaid or floor attendant, it is within the power of the guest to enter his room at any time that the dead-bolt 5 is not projected. It is also possible for the floor attendant to enter the room so long as the dead-bolt is not projected. If however the guest has entered and has projected the dead-bolt from the inside the floor attendant is shut out, but access may be had to the room by the owner of a special emergency key E shown in Fig. 6. If the room is empty, and if for any reason the proprietor wishes to close the room off, he may, by the use of the emergency key E project the dead-bolt from the outside, thus making it impossible for any one using the regular key to gain admission. While I have shown the special or emergency key as longer than the other key it will be understood that there are various ways of making the special key differ from the regular key so as to attain the ends sought. For convenience of expression I have referred to the key such as provided to a guest or floor attendant as a regular key, and the key held by the proprietor or superintendent as a special key.

I claim:

1. In a lock, a latch-bolt, a dead-bolt, a combined dead-bolt operating and blocking roll-back, manually operable means to turn said roll-back from the inside of a door to which the lock is applied, and key operable means

to turn said roll-back from the outside of such a door, stop shoulders on the dead bolt and blocking means on opposite sides of the hub of said roll-back for endwise cooperation with said stop shoulders for the purpose described.

2. In a lock, a latch-bolt, a dead-bolt, a combined dead-bolt operating and blocking roll-back, manually operable means to turn said roll-back from the inside of a door to which the lock is applied and key operable means to turn said roll-back from the outside of such a door, stop shoulders on the dead-bolt and blocking means on the roll-back cooperating with said stop shoulders, said blocking means comprising radial arms on said roll-back for endwise cooperation with the stop shoulders.

3. In a lock, a latch-bolt, a dead-bolt, a combined dead-bolt operating and blocking roll-back, manually operable means to turn said roll-back from the inside of a door to which the lock is applied and key operable means to turn said roll-back from the outside of such a door, stop shoulders on the dead-bolt and blocking means on the roll-back cooperating with said stop shoulders, a lever on said dead-bolt acting between said roll-back and the key operable means to displace the roll-back from its blocking position.

4. In a lock, a latch-bolt, a dead-bolt, a combined dead-bolt operating and blocking roll-back, manually operable means to turn said roll-back from the inside of a door to which the lock is applied and key operable means to turn said roll-back from the outside of such a door, stop shoulders on the dead-bolt and blocking means on the roll-back cooperating with said stop shoulders, a lever on said dead-bolt acting between said roll-back and the key operable means to displace the roll-back from its blocking position, and means on the dead-bolt coacting with said roll-back to turn the latter as the dead-bolt is reciprocated.

5. In a lock, a latch-bolt, a dead-bolt, a combined dead-bolt operating and blocking roll-back, manually operable means to turn said roll-back from the inside of a door to which the lock is applied and key operable means to turn said roll-back from the outside of such a door, stop shoulders on the dead-bolt and blocking means on the roll-back cooperating with said stop shoulders, a lever on said dead-bolt acting between said roll-back and the key operable means to displace the roll-back from its blocking position, and means on the dead-bolt coacting with said roll-back to turn the latter as the dead-bolt is reciprocated, and a spring impelled means to move the roll-back to its dead-bolt blocking position when the dead-bolt reaches the end of its reciprocal movement.

6. In a lock, a latch-bolt, a dead-bolt, a combined dead-bolt operating and blocking

roll-back, manually operable means to turn said roll-back from the inside of a door to which the lock is applied and key operable means to turn said roll-back from the outside of such a door, stop shoulders on the dead-bolt and blocking means on the roll-back cooperating with said stop shoulders, a lever on said dead-bolt acting between said roll-back and the key operable means to displace the roll-back from its blocking position, and means to throw said roll-back to its blocking position at both extreme positions of said dead-bolt.

7. In a lock, a reciprocable dead-bolt, a roll-back for manually advancing and retracting the same and for blocking the same in its advanced and its retracted position; a key operable means for releasing said roll-back from its blocking positions and for reciprocating said dead-bolt, and connecting means between said dead-bolt and roll-back for rotating the latter from one blocking position to the other blocking position.

8. In a lock, a reciprocable dead-bolt, a roll-back for manually advancing and retracting the same and for blocking the same in its advanced and its retracted position, a key operable means for releasing said roll-back from its blocking positions and for reciprocating said dead-bolt, and connecting means between said dead-bolt and roll-back for rotating the latter from one blocking position to the other blocking position, and a spring means to move said roll-back into its blocking position.

9. In a lock, a reciprocable dead-bolt, a roll-back for manually advancing and retracting the same and for blocking the same in its advanced and its retracted position, a key operable means for releasing said roll-back from its blocking positions and for reciprocating said dead-bolt, connecting means between said dead-bolt and roll-back for rotating the latter from one blocking position to the other blocking position, and a spring latch bolt, said key operable means coacting therewith to retract the same.

10. In a lock, a reciprocable dead-bolt, a roll-back for manually advancing and retracting the same and for blocking the same in its advanced and its retracted position, a key operable means for releasing said roll-back from its blocking positions and for reciprocating said dead-bolt, connecting means between said dead-bolt and roll-back for rotating the latter from one blocking position to the other blocking position, and a spring latch bolt, said key operable means including a roll-back operable by one key to operate said latch bolt, and also including a shiftable roll back head operable by a different key to reciprocate said dead bolt.

11. In a lock, a reciprocable dead-bolt, a roll-back for manually advancing and retracting the same and for blocking the same

in its advanced and its retracted position, a key operable means for releasing said roll-back from its blocking positions and for reciprocating said dead-bolt, connecting means between said dead-bolt and roll-back for rotating the latter from one blocking position to the other blocking position, and a spring latch bolt, said key operable means including a roll back operable by one key to operate said latch bolt, and also including a shiftable roll back head operable by a different key to reciprocate said dead bolt and to also operate said latch bolt.
